UNITED STATES PATENT OFFICE.

HIRAM W. HIXON, OF NEW YORK, N. Y.

DAM AND METHOD OF CONSTRUCTING SAME.

1,419,852.

Specification of Letters Patent. Patented June 13, 1922.

Application filed November 1, 1921. Serial No. 512,073.

To all whom it may concern:

Be it known that I, HIRAM W. HIXON, a citizen of the United States, and a resident of the city of New York, borough of Manhattan, in the county and State of New York, have invented a new and Improved Dam and Method of Constructing Same, of which the following is a full, clear, and exact description.

10 This invention pertains to dams, dikes, or other similar structures of this character and also relates to a method of constructing the same.

Heretofore it has been found impossible 15 to profitably divert certain rivers or streams whose beds or banks are of solid rock and lie within deep canons or gorges, such as the Grand Canon of Colorado, in order to construct the usual forms of dams and therefore 20 in order to obviate the necessity of diverting a stream or river of this character, the present invention contemplates a dam and a method of constructing the same which renders such a project possible and 25 practical.

The invention further contemplates a 30 dam and a method of constructing the same in a simple, efficient, inexpensive and expeditious manner.

As a further object the invention aims to 35 produce a dam and method of dam construction which includes a novel means of anchorage for the dam, and means for permitting of the flow of the stream through its regular bed during its course of construction.

Further objects and advantages will be 40 more apparent, as the nature, purpose and use of the invention is more clearly understood from the following specification, claims and accompanying drawings, in which

Figure 1 illustrates diagrammatically a 45 transverse section through a gorge or canon illustrating the dam in its applied position.

Fig. 2 is a longitudinal sectional view thereof.

Referring to the drawings by character of reference, 10 designates a gorge or canon, 50 the bottom of which constitutes the bottom or bed 11 of a stream or river 12. The dam includes a body 12 consisting of rocks or stones of various sizes and an anchoring means 13, the latter consisting of a net or 55 mesh fabric having the interstices of a suitable size to permit of the normal flow

of the stream therethrough while the dam is in the course of construction. The anchoring means for the body of the dam is supported transversely of the bed 11 by 60 a plurality of suspension cables 14 attached at their lower ends to the upper edge of the net or fabric and at their upper ends to a supporting cable 15 anchored at its opposite ends by suitable anchoring devices 16 65 embedded in the opposite banks of the canon to dispose the same transversely thereof. The bottom portion of the net or fabric 13 is adapted to lie on the bottom or bed of the stream as at 17 with the remaining portion bowed or bellied down stream to produce a pocket in which the stones or rocks constituting the body of the dam are received. The stones or rocks are preferably blasted from the canon walls and filled 70 into the pocket so that the same are of gradually decreasing sizes from the outer side of the dam to its inner side whereby the smaller stones will fill the interstices between the preceding larger stones to 75 finally build up a substantially solid rear wall which will be gradually covered by mud or earth continuously washed thereupon from the bed or bottom of the river. The weight of the rocks or stones upon the portion 80 17 of the net or fabric will serve as a means for securely anchoring it to the bottom or bed of the stream whereby to prevent dislodgement thereof. In order to prevent dislodgement of the sides of the net, 85 the same is preferably anchored as at 18 to the sides of the canon wall from its upper edge to a point approximately level with the neutral level of the stream.

From the foregoing it follows that the 90 method of constructing a dam of this character essentially consists in the disposition of a foraminated anchoring net or fabric transversely of the bed of a stream, suspending the upper edge thereof from an overhead 100 support, weighting the lower edge of said anchoring net or fabric to the bottom or bed of the stream to dispose the lower edge down stream and out of vertical alignment with the upper edge of the net to dispose the net 105 at an angle to the vertical, piling rocks or stones of gradually decreasing sizes from the outer to the inner side of the dam body thus formed whereby to gradually cut off the flow of the stream therethrough and 110 force said flow over the top of the dam to raise the level of the stream above the dam.

2
 While there has been illustrated and described a single and preferred embodiment of the invention, it is to be understood that the right is reserved to embodiments other than those actually illustrated herein to the full extent indicated by the general meaning of the terms in which the claims are expressed and by variations in the phraseology of the same.

10 I claim:

1. A dam construction including a body consisting of stones of various sizes and a net for positioning and anchoring the dam body in the bed of a stream, said net being bellied down stream to provide a pocket for the reception of the stones upon the lower edge of which the same will rest to anchor the same to the bottom or bed of the stream, and a suspension means for anchoring the upper edge of said net.

2. A dam construction comprising a dam body consisting of rocks or stones, a foraminated anchoring means arranged transversely of the stream, a supporting cable anchored at the opposite ends to the opposite banks of the stream, and a suspension means attached respectively to the cable and the upper edge of the anchoring means, said anchoring means being bellied down stream with its lower portion disposed up stream and lying on the bottom of the bed of the stream, whereby to provide a pocket for the reception of the rocks or stones constituting the dam body.

3. A dam construction comprising a dam body consisting of rocks or stones, a foraminated anchoring means arranged transversely of the stream, a supporting cable anchored at the opposite ends to the opposite banks of the stream, and a suspension means attached respectively to the cable and the upper edge of the anchoring means, said anchoring means being bellied down stream with its lower portion disposed up stream and lying on the bottom of the bed of the stream, whereby to provide a pocket for the reception of the rocks or stones constituting the dam body, said rocks or stones being of various sizes with the larger ones arranged adjacent the outer side of the dam and of gradually decreasing sizes toward the inner side of the dam, as and for the purpose specified.

4. A dam including a body consisting of rocks or stones of various sizes, a cable anchored at its opposite ends to the banks and arranged transversely of the stream to be dammed, and a net suspended therefrom having its lower portion directed up stream resting upon the bed of the stream and bellied down stream to provide a pocket for the reception of the rocks or stones which are arranged therein with the larger ones adjacent the net and forming the outer side of the dam, and the remainder arranged in layers of gradually decreasing sizes toward the inner side of the dam.

HIRAM W. HIXON.
